poration of Delaware

Application November 5, 1937, Serial No. 173,038

18 Claims. (Cl. 260—402)

This invention relates to an improved process for preparing certain chemical compositions especially useful as wetting agents, detergents, foaming agents, emulsifying agents, and the like. More particularly, the invention concerns a simple process for preparing a concentrated neutralized organic sulphonate produced by reacting a polyhydric alcohol, a sulphonating agent, an aromatic material and a fatty oil or fatty acid, which process may conveniently be operated continuously. This process makes it possible to manufacture chemical compositions with excellent wetting, deterging, emulsifying, penetrating, dispersing and lathering properties at a very low cost.

In U. S. Patent 2,014,502, granted Sept. 17, 1935 to Karl Marx, Karl Brodersen and Matthias Quaedvlieg, a process is described which essentially consists in reacting with a condensing and sulphonating agent a mixture of an aromatic hydrocarbon of the benzene or naphthalene series and a mono ester or a polyhydric alcohol with a higher fatty acid, the alkali salts of which have soap characteristics, said ester having at least one free hydroxyl group.

According to the present invention, compositions similar to those described in the Marx et al. patent may be manufactured by an economical process which is relatively simple in operation and readily adaptable to a continuous procedure. By the present process, one is able to prepare a purer type product because of the controlled reaction conditions. For example, the temperature of the reaction may be relatively low, preferably between normal room temperature and 80° C., whereas prior processes of this type are usually conducted at much higher temperatures. Furthermore, a fatty oil may be used directly as one of the reactants, thus saving considerable time and effort over those processes which require the separation of the fatty acid from the fatty oil and the preparation of the monoglycerides thereof, which steps tend to cause serious discoloration of the fatty acid compound.

A novel procedure for neutralization of the complex reaction product prevents any detrimental effects of the alkali on the sulphonated reaction product but still permits the use of concentrated solutions of both the reaction product and alkali, thus obtaining concentrated solutions of the neutralized material without the numerous process steps. Heretofore, it has been necessary to use dilute solutions of both the reaction product and the alkali and then to concentrate the resulting dilute solution of the neutralized prod-

uct, this latter step almost invariably impairing the general appearance and effectiveness of the detergent product.

Uniform products and high yields are obtained by careful control of the sulphonating agent so that the concentration of the acid at the close of the reaction is relatively high. When the acid is within the preferred range of concentration at the close of the reaction the variable factors of original concentration, strength of acid and the amount of water present and generated in the reaction, do not prevent the completion of the reaction and the final products have good color and odor and are relatively uniform in composition.

In its preferred form, the new process comprises the steps of continuously mixing a sulphonating agent and a polyhydric alcohol; adding to this mixture continuously and with agitation, fatty oil and aromatic material, and after completion of the reaction, continuously neutralizing the product by bringing it into confluence with a relatively concentrated solution of a neutralizing agent, with agitation, and in the presence of a relatively large body of already neutralized reaction product so as to have conditions of substantial neutrality during this step.

By this process, using but two small mixers, and a neutralizer, which is also small as compared with the equipment ordinarily used for making soap or other detergent materials, the raw materials may be supplied to one end of the apparatus and the finished product withdrawn from the other without any interruption to the continuous flow.

The proportions of material to be used in the new process may be varied somewhat within the scope of this invention, but it has been found preferable to use such proportion of fatty oil or fatty acid and polyhydric alcohol as will, when reacted, yield mono esters and leave a small excess of polyhydric alcohol. Thus when a fatty oil and glycerine are used, it is preferable to use one molecular proportion of the fatty oil, two molecular proportions plus around 5 per cent of substantially anhydrous glycerine. If a fatty acid is substituted for a fatty oil, it is preferable to use one molecular proportion of fatty acid to one molecular proportion of anhydrous glycerine, plus an excess of 3 or 4 per cent. Approximately one molecular weight of the aromatic material will ordinarily be used for each molecular weight of the finished product that is to be made.

Enough of the sulphonating agent should be used and the concentration adjusted to be such

that the final product will be completely mono-sulphonated, and substantially completely soluble in water. It has been found that, if the sulphuric acid used, usually fuming acid, is of such 5 concentration and quantity that the sulphuric acid which remains after the reaction has been completed is of a concentration of around 99 per cent, the reaction will be substantially complete. If the concentration of the sulphuric acid at the 10 end of the reaction is appreciably less than this, the reaction will not be complete and the reaction time relatively long. If appreciably greater than 99%, then undesirable by-products will be formed and the product will be poorer in color 15 and odor. If a poly-sulphonated compound is desired, the molecular proportion of the sulphonating agent should be correspondingly increased so that the product which will be formed contains the desired number of sulphonate radicles 20 in the aromatic nucleus.

To illustrate the present process, the following specific example is given:

64 parts by weight of anhydrous glycerine (99.5%) may be mixed with 526 parts by weight 25 of fuming sulphuric acid (102.8%) at 30° C. and the resulting mixture stirred with 216 parts by weight of cocoanut oil, and 128 parts by weight of naphthalene at 80° C. or slightly less. The reaction will be completed within approximately 30 40 minutes, and the product may be neutralized with a 30 per cent aqueous solution of caustic soda at a temperature of around 40° C. to a pH. between 6.0 and 7.0. The neutralized product may then be dried in a spray tower to a white 35 granular non-hygroscopic powder. Alternatively, the product may be dried on soap drying rolls, mixed with perfume, fillers, additional glycerine or other materials commonly added to soap and formed into bars or cakes.

40 Although the order of the process is preferably that described above and that which is shown by the drawings, it is possible to accomplish a similar result by mixing the fatty oil or fatty acid, glycerine, or other polyhydric alcohol, aromatic 45 material and sulphonating agent in any other order that may be desired. For example, fatty oil or fatty acid may be mixed with glycerine, and if desired reacted by heating with or without a catalyst, prior to the addition of the aromatic 50 material and sulphonating agent. Alternatively, the sulphuric acid or other sulphonating agent may be reacted with the aromatic material prior to the addition of the glycerine and fatty oil or fatty acid. It has been found that, in general, 55 it is not desirable to allow the sulphonating agent to act on the fatty oil prior to the addition of the other ingredients, because the sulphonating agent tends to char the oil and thus darken the final product.

60 The drawings appended to this application show a system of apparatus for accomplishing the process as briefly outlined in the foregoing description. It is to be understood, however, that the process can be performed by other apparatus 65 than that shown in these drawings and that various modifications in the process and apparatus, obvious to those skilled in the art, may be made.

Fig. 1 is a plan view of the apparatus adapted 0 to perform the preferred process of this invention;

Fig. 2 is a side elevation view of a portion of the apparatus shown in Fig. 1;

Fig. 3 is a side elevation view of the spray dryer shown in Fig. 1;

Fig. 4 is an end view of the apparatus shown in Fig. 2;

Figs. 5 and 6 are sectional views through the first and second mixers, respectively;

Figs. 7 and 8 are sectional views taken on lines 1-1 and 8-8 of Fig. 5, respectively;

Fig. 9 is a vertical sectional view of the neutralizer; and

Fig. 10 is a horizontal sectional view of the neutralizer taken on the line 10-10 of Fig. 9. 10

The apparatus illustrated in the drawings is a plant installation adapted for the continuous performance of the preferred process of this invention. In describing the operation of this apparatus, reference will be made to the raw materials 15 as sulphuric acid, glycerine, cocoanut oil, naphthalene and caustic soda. It is to be understood, however, that these are used merely as preferred examples, and other equivalent materials or mixtures of the materials may be used instead. With 20 this understood, it may be said generally that the apparatus operates first to mix the glycerine and sulphuric acid, then to react the mixture with cocoanut oil and naphthalene, and thereafter to neutralize the glycerine-acid-cocoanut oil-naphthalene product with caustic soda.

According to the preferred mode of applying the principles of this invention, substantially anhydrous glycerine (around 99.5%) is supplied through pump 11 and pipe 12 to the first mixer 30 13. At the same time, fuming sulphuric acid (around 102.8%) is supplied through a pump 14 and pipe 15 to the same mixer. The pumps 11 and 14 and the pump for the fatty oil which will later be described are preferably geared together 35 so that each will supply its respective reactant in exactly the desired proportion. Numerous types of proportioning devices are known, and any one of these which is found suitable may be used in place of the pumps shown. As an additional precaution to permit certainty with respect to the proportions of the reactants entering the mixer 13, volumeters or flow meters 16 and 17 may be connected to the glycerine pipe 12 and the sulphuric acid pipe 15, respectively, near the point where the pipes connect to the mixer. Volumeters are calibrated vessels arranged to be filled, and the time of filling noted by a stop 40 watch so as to calibrate or adjust the proportioning mechanism. They drain back to the storage tanks after use. 45

50 As illustrated in Figs. 5, 7 and 8, the mixer 13 consists of a cylindrical shell 18 closed at the bottom except for a drain opening 19. The top of the mixer is closed by a cover 20 upon which is mounted a driving motor 21 and suitable gearing 22 shown in Fig. 2. Through the top of the mixer a rotatably mounted vertical shaft 23 extends, and this shaft is connected to the motor 21 through the gearing so that it may be driven 55 thereby. A series of radially extending mixing paddles 24, 25 and 26 are carried by shaft 23, and these paddles are constructed for movement within spaces arranged between hollow annular members 27 and 28 positioned within the cylinder. 60 Cooling water is circulated through the hollow members by means of pipe connections as shown in Fig. 2.

65 As illustrated particularly in Figs. 5 and 8, the paddles and the annular cooling members vary 70 somewhat in form. The four upper cooling members 27 are somewhat smaller in diameter than the inside of the shell 18 and are connected to their outer edges by cylindrical rings so that a portion of the liquid in the mixer may flow up.

wardly from below the fourth member between the wall of the mixer and the peripheries of these upper annular members and thus be mixed thoroughly with the fresh liquid as it enters the mixer. 5 This action is aided by the construction of the paddles in the upper part of the mixer. Each of the three upper paddles 25 consists of a flat circular plate with four vanes extending helically above it to throw the liquid outwardly and 10 four helical vanes below the plate to draw the liquid inwardly and propel it downwardly through the center opening in the underlying cooling element. The flat circular portions of the paddles completely prevent any of the liquid from passing 15 directly downward along the shaft 23. All of the liquid is thus forced to travel out and around the edges of the circular portions of each of these three upper paddles. The fourth paddle from the upper end is an impeller 25 which must finally 20 be passed by the liquid before it enters the lower part of the mixer. This impeller is of similar construction to the first three paddles excepting that the four vanes above and the four vanes below the paddle are all arranged to throw the 25 liquid upwardly and thus force a part of the liquid to return to the top of the mixer, and in- ducing a maximum mixing action.

The two lower cooling members 26 are fit snug- 30 ly to the shell by ring members and therefore all the liquid which passes these members must pass through the openings therein which surround the center shaft 23, and none can pass upwardly around the outside. Paddles 26 lying below the 35 fifth and sixth cooling member are but doubly radially projecting arms fastened to the shaft 23. A cross member 29 is provided at the bottom of the mixer, and this cross member carries a pin 30 which enters an actual opening in the lower 40 end of the shaft 23 to maintain the shaft in alignment. Cross member 29 is further provided with a pair of baffles 31 which retard any rotation of the mixer and direct the liquid through the drain opening 19.

As will appear upon consideration of Figs. 45 4 and 5, the glycerine and sulphuric acid enter the mixers from pipes 12 and 15 and are released into the mixer at the top and near its center. They progress downwardly through the mixer as they become mixed and the mixture passes out 50 through the drain opening 19. As the glycerine and sulphuric acid are mixed, cooling water is circulated through the cooling members 27 and 28 to keep the temperature sufficiently low to prevent darkening of the material. It has been 55 found that a temperature of approximately 30° C. is sufficiently low for this purpose, although lower temperatures may be used and slightly higher temperatures may be permitted without serious results.

60 Suitable pipes 32 are provided to supply water to the cooling members, the arrangement being such that the cooling water first enters the lower one of the four upper cooling members 27 from which it progresses upwardly to the top cooling member. It is thereafter conducted to the sixth or bottom cooling member 28 and then to the fifth cooling member and finally discharged. This arrangement has been found to be especially 65 desirable because it maintains a fairly even tem- perature throughout the mixture, the greatest cooling effect being produced in the upper portion of the mixer where the initial mixing takes place and the tendency for the compounds to re- act and evolve heat is the greatest.

70 75 From the bottom of mixer 13 the glycerine-

sulphuric acid mixture is conveyed by pipes 33 to a second mixer 34 at a point near the top. Cocoanut oil and naphthalene also enter this second mixer at a point near the top, being supplied by pump 35 and hopper 71 through pipe 36 and dry powder feeder 72 and chute 73, respec- 5 tively. The pump 35 is connected so as to supply a quantity of fatty oil accurately proportioned to the amounts of glycerine and sulphuric acid supplied by pumps 11 and 14, respectively. 10 The quantity of naphthalene added from hopper 71 is accurately proportioned to the amounts of fatty oil, glycerine and sulphuric acid entering the second mixer by means of an accurately controlled weighing system which regulates the dry 15 powder feeder 72. Numerous types of weighing systems are known and any one of these which is found suitable and which gives the desired degree of accuracy may be used. As with the glycerine and sulphuric acid, the volumeter or flow meter 20 37 is provided for the cocoanut oil. This device is connected to pipe 36 at a point near the top of the second mixer so that the proportion of cocoanut oil entering this mixer may be readily 25 determined.

The construction of the second mixer 34 is sub- 30 stantially the same as that of the first mixer 13 so that it need not be described in detail, al- though it has been shown in Fig. 6. The heat transfer means which are cooling members in the 35 first mixer are used as heating members in the second mixer and hot water is passed there- through to effect the heating. The hot water need not be circulated through the members in the order that the cooled water is circulated through the cooling members in the first mixture, but instead, the water may first enter the top 40 heating member and then progress downwardly through the next adjacent members in regular order to the lowest member from which it is discharged.

Furthermore, there are but two of the smaller sized heat transfer members at the top of the second mixer, and only one of the paddles has its 45 vanes arranged to throw outwardly above and draw inwardly below the flat circular portion. All of the vanes on the second paddle throw out- 50 wardly. The lower part of the second mixer in- cludes only heat transfer members fitted closely in the shell, and only double bladed radially 55 extending mixing paddles are employed there- between. Preferably the average temperature in this mixer is around 50° C.

From the bottom of the second mixer the gly- 60 erine-acid-cocoanut oil-naphthalene reaction 65 product is conveyed to the top of the neutralizer 39 by transfer line 38. The neutralizer com- prises a large cylindrical tank that contains mix- ing and cooling equipment sufficient to thor- 70oughly mix, at a controlled temperature, the 60 glycerine-acid-cocoanut oil-naphthalene prod- 75 uct with a neutralizing material which is pre- ferably caustic soda. The caustic enters the upper part of the mixer through a pipe 40 pre- ferably as a solution of 30-50% concentration, 80 being discharged into the neutralizer at about the same point as the reaction product so that the two materials pass into immediate con- fluence and the process of neutralization begins 85 at once. Upon the admission of the caustic and the reaction product into the neutralizer, the materials first pass downwardly through a cool- 90 ing cylinder 41 and then upwardly between the outside of this cylinder and the wall of the neu- tralizer, which wall forms an additional cooling 95

surface 42. Upon circulating to the upper end of the neutralizer, a part of the neutralized product is drawn off from the outside of the neutralizing cycle through pipe 43 and conveyed to the drying equipment. The remainder is recycled with the incoming reaction product and caustic solution.

In order to thoroughly mix the caustic solution and the reaction product, agitation is provided in the form of a shaft 44 which extends downwardly through the top of the neutralizer and axially through the center of the inner cooling cylinder 41. This shaft is driven by an electric motor 45 through suitable gearing all mounted on the top of the neutralizer. Shaft 44 carries a series of impellers 46 within the inner cooling cylinder and a larger impeller 47 which is below the bottom of the inner cooling cylinder 41 for the circulation of the mixture. Appropriately shaped deflecting members 48 and 49 are provided to direct the mixture into the large impeller member 47 so as to obtain a maximum circulatory effect. In the inner cooling cylinder 41 there is an axially extending cooling coil 50 which provides additional cooling surface, and a cooling water is fed through this coil into the bottom of the inner cooling cylinder and finally withdrawn from the top of that cylinder.

Between the inner and outer cooling cylinders 41 and 42 are a series of scrapers that continually remove any of the product that solidifies upon the cooling surface. As shown in Figs. 9 and 10, these scrapers comprise vertically extending straps 51 and 52 attached to the upright supporting members 55 and 56 and pressed against the inner and outer cooling cylinders respectively, by springs 53 and 54. The supporting members are in turn mounted upon a spider 57 carried at the center of the bottom of the neutralizer 40 tank upon a rotatable shaft 58 that extends through the bottom of the tank to suitable driving mechanism 59 and motor 60. The lower end of the agitator shaft 44 is rotatably received in a cavity in the upper end of the shaft 58. Braces 45 61 and 62 may be used to join the scraper supporting members 55 and 56, respectively, so as to make a more rigid construction.

In order to control the amount of caustic added in accordance with the amount necessary to just neutralize the reaction product, a device is connected to the neutralizer for continuously measuring the hydrogen ion potential (pH) of the neutralized product, and this device controls an electrically operated valve 63 in the caustic line 55 40. The measuring device comprises a sampling pipe 64 through which a small amount of the mixed material is continually withdrawn from a point near the bottom of the inner cooling cylinder by the action of a small pump 65. From the 60 pump the material is discharged to a baffle tank 66 in which are electrodes 67 connected to operate the electrically operated valve 63 through an electrometric titration device 68. Thus the amount of caustic supplied is controlled so as to 65 always be just sufficient to neutralize the reaction product, and the neutralized material may be kept accurately at a pH of around 6.0 to 7.0, which has been found highly preferable. The material flowing through the baffle tank is 70 turned to the neutralizer by pipe 69.

After the product leaves the neutralizer, it is preferably conveyed by the pipe 43 to a spray drying device such as shown in Fig. 3 and described in Patent 1,652,900, patented to Dallas R. Lamont on December 13, 1927. Since this par-

ticular equipment is described in detail in that patent, it will be referred to here only in general terms. The neutralized reaction product of this invention together with a considerable amount of water which still remains with it is separated in a fine state of subdivision into a drying chamber 70 near the upper end. As it falls, it is contacted by a large volume of air forced down through the chamber by suitable pumping mechanism. By the time the product reaches the bottom of the chamber, it is dry and in the form of beads. These are drawn off in a current of air to the cyclone separator 74 where they are separated from the air in a form that is ready for packaging.

With the new product, there appears to be considerable advantage to spray drying, although, of course, the product may be dried in other ways if desired. However, if the product is spray dried, it forms beautiful, exceptionally white beads that dissolve instantly in water either hot or cold. While the apparatus described has been arranged to mix the glycerine and sulphuric acid prior to reacting them with the cocoanut oil and naphthalene, it is to be understood that this is only the preferred form and that other arrangements may be made. For example, glycerine and the cocoanut oil may be mixed in one mixer and the product sulphonated in the second mixer with a mixture of sulphuric acid and naphthalene, or cocoanut oil, glycerine and naphthalene may be mixed in the first mixer and sulphonated in the second mixer with sulphuric acid. Also, lime or other alkaline reagents may be used to effect the neutralization of the product and suitable means provided to settle, filter or centrifuge the product to remove the precipitate. Likewise, the electrometric titration apparatus may be changed to any desired form or even eliminated altogether.

As has been indicated above, the specific reactants mentioned as examples in the description of the process are not the only reactants that can be used according to this invention. For example, it is possible to use in place of cocoanut oil any other fatty oil of a generally similar nature, such as palm oil, olive oil, tallow, soy bean oil, fish oils, cottonseed oil, castor oil, peanut oil, rape oil, the fatty acids from any of these oils, naphthenic acid, abietic acid, or carboxylic acids formed by the oxidation of paraffin hydrocarbons. Glycol, diethylene glycol or other polyglycols or polyglycerols may be used in place of glycerine. Similarly, chlor sulphonic acid or sulphur trioxide may be used in place of fuming sulphuric acid to perform the sulphonation and condensation. Other aromatic materials than naphthalene may also be used, as examples of which cresol, xylenol, benzol, benzyl naphthalene, toluol, pyrogallol, resorcinol, isobutylphenol and anthracene may be mentioned. Obviously, it will be necessary to modify the reaction conditions somewhat to compensate for the varying characteristics of the materials used, but the same general process of reaction will apply.

The final product which is formed by neutralizing with caustic soda will contain an appreciable amount of sodium sulphate formed in the neutralization and this can either be removed or left in the final product according to the characteristics desired in that product. Sodium sulphate is not harmful to the effectiveness of the product other than that it reduces the percentage of active ingredient in the final product, and for some purposes this is desirable. To re-

move the sodium salt base, the final product may be extracted with butyl alcohol or similar water insoluble alcohol which will dissolve the reaction product, or the process itself may be modified to avoid the formation of the sodium sulphate. If the product is neutralized with lime instead of with caustic soda, the resultant product contains calcium sulphate which is relatively insoluble and may be easily separated from the active ingredient. A 10% slurry of lime has been found entirely satisfactory for this purpose. The triethanolamine salts of the reactant product or the magnesium, ammonium, potassium or other salts may be made by simple base exchange reactions with the calcium salt of the reaction product. In performing such a reaction, a salt of the triethanolamine, ammonium, potassium, or magnesium is used, which salt will precipitate calcium from the solution and permit the desired base to replace it. Such salts are the oxalates, carbonates, phosphates, or the like.

The final product may be made into powders, solutions, emulsions, either plastic or liquid, flakes, chips, bars, beads, or any of the other forms into which soap can ordinarily be made. It is compatible with not only the substances with which soap is compatible, but with a great many substances that are more acidic or more basic than can be satisfactorily used with soaps. Fillers that may be used include talc, pumice, sodium silicate, bentonite, feldspar, various inorganic salts such as Glauber salt and chalk; germicides such as phenol, hexylresorcinol and mercury chloride may also be incorporated with the material without injury either to the effectiveness of the organic reaction product or the germicide. Perfumes and flavorings including organic compounds unstable in the presence of alkalis, such as isoeuginol, lanolin, and methylanthranilate; mildly acidic astringents such as aluminum chloride, zinc sulphate and alum, deodorants, fatty acids, preservatives, starch, waxes, water and pigments and dyes of various kinds may all be used in almost any desired combination or proportion.

We claim:

1. A process for preparing a material suitable for use as a detergent that comprises reacting a material of the class consisting of fatty oils and fatty acids with a polyhydric alcohol, a sulphonating agent, and an aromatic compound of the class consisting of compounds of the benzene, naphthalene and anthracene series, and thereafter neutralizing the reaction product by bringing the concentrated reaction product into confluence with a relatively concentrated solution of a neutralizing agent in the presence of a considerable quantity of already substantially neutralized material.

2. A process for preparing a material suitable for use as a detergent that comprises reacting a material of the class consisting of fatty oils and fatty acids with a polyhydric alcohol, a sulphonating agent, and an aromatic compound of the class consisting of compounds of the benzene, naphthalene and anthracene series, and thereafter neutralizing the reaction product by bringing the concentrated reaction product into confluence with a concentrated solution of a neutralizing agent in the presence of an excess of already substantially neutralized product at a temperature of around 40° C.

3. A process for preparing a material suitable for use as a detergent that comprises continuously reacting a material of the class consisting of

fatty oils and fatty acids with a polyhydric alcohol, a sulphonating agent and an aromatic compound of the class consisting of compounds of the benzene, naphthalene and anthracene series at temperatures ranging from approximately 30° C. to 80° C. and thereafter continuously neutralizing the reaction product by continuously bringing the reaction product into confluence with a concentrated solution of a neutralizing agent in the presence of an excess of already substantially neutralized product.

4. A process for preparing a material suitable for use as a detergent that comprises mixing a polyhydric alcohol and a sulphonating agent at a temperature of around 30° C. and condensing the mixture with an aromatic compound of the class consisting of compounds of the benzene, naphthalene and anthracene series and a material of the class consisting of fatty oils and fatty acids at a temperature of approximately 80° C. and thereafter neutralizing the final product by bringing the concentrated reaction product into confluence with a concentrated solution of a neutralizing agent in the presence of an excess of already substantially neutralized product at a temperature of around 40° C.

5. A process for preparing a material suitable for use as a detergent that comprises reacting a material of the class consisting of fatty oils and fatty acids with a polyhydric alcohol, a sulphonating agent, and an aromatic compound of the class consisting of compounds of the benzene, naphthalene and anthracene series, and thereafter neutralizing the reaction product by bringing the concentrated reaction product into confluence with a concentrated solution of a neutralizing agent in the presence of an excess of already substantially neutralized product and regulating the proportion of neutralizing agent to be added in accordance with the pH of the substantially neutralized product so as to maintain the pH thereof between 6.0 and 7.0.

6. A process for preparing a material suitable for use as a detergent that comprises reacting approximately one molecular proportion of fatty oil, a slight excess over two molecular proportions of a polyhydric alcohol, an excess over three molecular proportions of a sulphonating agent and approximately three molecular proportions of an aromatic compound of the class consisting of compounds of the benzene, naphthalene and anthracene series, and thereafter neutralizing the concentrated reaction product by bringing the same into confluence with a concentrated solution of a neutralizing agent in the presence of an excess of already substantially neutralized product.

7. A process for preparing a material suitable for use as a detergent that comprises reacting approximately one molecular proportion of a fatty acid, a slight excess over one molecular proportion of a polyhydric alcohol, an excess over one molecular proportion of a sulphonating agent and approximately one molecular proportion of an aromatic compound of the class consisting of compounds of the benzene, naphthalene and anthracene series and thereafter neutralizing the concentrated reaction product by bringing the same into confluence with a concentrated solution of a neutralizing agent in the presence of an excess of already substantially neutralized product.

8. A process for preparing a material suitable for use as a detergent that comprises reacting approximately one molecular proportion of coconut oil, around 5% more than two molecular

- proportions of substantially anhydrous glycerine, an excess over three molecular proportions of fuming sulphuric acid (approximately 102.8%), approximately three molecular proportions of 5 naphthalene and neutralizing the concentrated reaction product with a concentrated solution of caustic soda (approximately 30%) to a pH of 6.0 to 7.0 in the presence of an excess of already substantially neutralized product.
- 10 9. A process for preparing a material suitable for use as a detergent that comprises reacting a material of the class consisting of fatty oils and fatty acids with a polyhydric alcohol, a sulphonating agent, and an aromatic compound of the 15 class consisting of compounds of the benzene, naphthalene and anthracene series, said sulphonating agent being of the amount and concentration such that after the completion of the reaction the residual acid will possess a concentration of around 99% sulphuric acid or slightly above, and thereafter neutralizing the reaction product by bringing the reaction product into confluence with a concentrated solution of a neutralizing agent in the presence of an excess of 20 already substantially neutralized product.
- 10 10. A process for preparing a material suitable for use as a detergent that comprises introducing a polyhydric alcohol and a sulphonating agent into a mixing zone, cooling and agitating the 25 materials in the said zone, transferring the mixture of materials so formed to a second mixing zone, introducing an aromatic compound of the class consisting of compounds of the benzene, naphthalene and anthracene series and a material of the class consisting of fatty oils and fatty acids into said second mixing zone with said mixture, agitating and heating the material in said second mixing zone, transferring the product to a neutralizing zone, maintaining an excess of already substantially neutralized products in said neutralizing zone, bringing a concentrated solution of a neutralizing agent into confluence with the reaction product in said neutralizing zone, regulating the amount of neutralizing agent introduced so as to maintain the pH of the relatively large body at a pH of around 30 6.0 and 7.0.
11. A process for preparing a material for use as a detergent that comprises continuously reacting approximately one molecular proportion of fatty oil, a slight excess over two molecular proportions of a polyhydric alcohol, an excess over three molecular proportions of a sulphonating agent and approximately three molecular proportions of an aromatic compound of the class consisting of compounds of the benzene, naphthalene and anthracene series, and thereafter continuously neutralizing the concentrated reaction product by continuously bringing the reaction 35 product into confluence with the concentrated solution of a neutralizing agent in the presence of an excess of already substantially neutralized product.
12. A process for preparing a material suitable for use as a detergent that comprises continuously reacting approximately one molecular proportion of a fatty acid, a slight excess over one molecular proportion of a polyhydric alcohol, an excess over one molecular proportion of a sulphonating agent and approximately one molecular proportion of an aromatic compound of the class consisting of compounds of the benzene, naphthalene and anthracene series, and thereafter continuously neutralizing the concentrated reaction product by continuously bringing the 40 reaction product into confluence with a concentrated solution of a neutralizing agent in the presence of an excess of already substantially neutralized product.
13. A process for preparing a material suitable for use as a detergent that comprises reacting a material of the class consisting of fatty oils and fatty acids with glycerine, fuming sulphuric acid and naphthalene and thereafter neutralizing the reaction product by bringing the concentrated reaction product into confluence with a relatively concentrated solution of a neutralizing agent in the presence of a considerable quantity of already substantially neutralized product. 45
14. A process for preparing a material suitable for use as a detergent that comprises reacting a material of the class consisting of fatty oils and fatty acids with glycerine, fuming sulphuric acid and cresol and thereafter neutralizing the reaction product by bringing the concentrated reaction product into confluence with a relatively concentrated solution of a neutralizing agent in the presence of a considerable quantity of already substantially neutralized product. 50
15. A process for preparing a material suitable for use as a detergent that comprises reacting a material of the class consisting of fatty oils and fatty acids with glycerine, fuming sulphuric acid and an aromatic compound of the class consisting of compounds of the benzene, naphthalene and anthracene series and thereafter neutralizing the reaction product by bringing the concentrated reaction product into confluence with a relatively concentrated solution of a neutralizing agent in the presence of an excess of already substantially neutralized product. 55
16. A process for preparing a material suitable for use as a detergent that comprises continuously introducing a polyhydric alcohol and a sulphonating agent into a mixing zone, continuously transferring the mixture of materials so formed to a second mixing zone, continuously introducing an aromatic compound of the class consisting of compounds of the benzene, naphthalene and anthracene series and a material of the class consisting of fatty oils and fatty acids into said second mixing zone with said mixture, agitating and heating the material in said second mixing zone, continuously transferring the product to a neutralizing zone, maintaining an excess of already substantially neutralized product in said neutralizing zone, continuously bringing a concentrated solution of a neutralizing agent into confluence with the reaction product in said neutralizing zone, regulating the amount of neutralizing agent introduced so as to maintain the pH of the relatively large body at a pH of around 60 6.0 to 7.0.
17. A process for preparing a material suitable for use as a detergent that comprises continuously reacting a material of the class consisting of fatty oils and fatty acids with a polyhydric alcohol, a sulphonating agent and an aromatic compound of the class consisting of compounds of the benzene, naphthalene and anthracene series, said sulphonating agent being of the amount and concentration such that after the completion of the reaction the residual acid possesses a concentration of around 99% sulphuric acid, or slightly above, and thereafter continuously neutralizing the reaction product by continuously bringing the reaction product into confluence with a concentrated solution of a neutralizing agent in the presence of an excess of already substantially neutralized product. 65 70 75

18. A process for preparing a material suitable for use as a detergent that comprises reacting a material of the class consisting of fatty oils and fatty acids with glycerine, fuming sulphuric acid and benzyl naphthalene and thereafter neutralizing the reaction products by bringing the condensation reaction products into confluence

with a relatively concentrated solution of a neutralizing agent in the presence of a considerable quantity of already substantially neutralized product.
